162,613

CHILD'S BATHROOM TRAINING UNIT

Douglas A. Ball and Herbert E. Osborn,
Fort Worth, Tex.

Application February 16, 1950, Serial No. 7,962

Term of patent 14 years
(Cl. D4—4)To all whom it may concern:

Be it known that we, Douglas A. Ball and Herbert E. Osborn, both citizens of the United States and both residing at Fort Worth, in the county of Tarrant and State of Texas, have invented a new, original, and ornamental Design for a Child's Bathroom Training Unit, of which the following is a specification, reference being had to the accompanying drawings, forming part thereof.

Figure 1 is a front elevational view of a child's bathroom training unit, showing our new design. Figures 2 and 3 are, respectively, side and plan views of the child's bathroom training unit illustrated in Figure 1. Figure 4 is a perspective view of our design.

We claim:

The ornamental design for a child's bathroom training unit, substantially as shown.

DOUGLAS A. BALL.
HERBERT E. OSBORN.
